United States Patent Office

Des. 193,608
Patented Sept. 18, 1962

193,608

VACUUM CLEANER OR THE LIKE

Ralph A. W. Johanson, White Plains, N.Y., assignor to
Electrolux Corporation, Old Greenwich, Conn., a cor-
poration of Delaware

Filed Sept. 8, 1961, Ser. No. 66,658

Term of patent 14 years

(Cl. D9—2)

Fig. 2

Fig. 4

Fig. 3

FIG. 1 is a perspective view of a vacuum cleaner embodying my new design;

FIG. 2 is a top view thereof;

FIG. 3 is a side view thereof; and

FIG. 4 is a rear view thereof. It is understood that the grille fragmentarily shown is continuous throughout the area designated.

The side opposite that shown in FIG. 3 is a mirror image thereof.

I claim:

The ornamental design for a vacuum cleaner or the like, as shown and described.
